UNITED STATES PATENT OFFICE.

JOHN A. ERICKSON, OF FAIRVIEW, UTAH.

PLOW-MOUNTING MECHANISM.

1,189,927.

Specification of Letters Patent.

Patented July 4, 1916.

Application filed November 9, 1914. Serial No. 871,072.

To all whom it may concern:

Be it known that I, JOHN A. ERICKSON, a citizen of the United States, residing at Fairview, in the county of Sanpete and State 5 of Utah, have invented certain new and useful Improvements in Plow-Mounting Mechanism; and I do declare the following to be a full, clear, and exact description of the invention, such as will enable others skilled 10 in the art to which it appertains to make and use the same.

My invention relates broadly to improvements in agricultural implements and more particularly to plow mounting mechanism 15 for use in connection with motor driven plows.

The object of the invention is to improve upon the construction of devices of this general character to such an extent as to provide 20 a machine which will be simple, strong and efficient in operation and which will readily perform the functions for which it is designed.

With the above and minor objects in view, 25 the invention resides in certain novel features of construction and combination herein described and claimed and shown in the drawings wherein—

Figure 1 is a central vertical longitudinal 30 section of the machine with the plows raised; Fig. 2 is a detail section similar to Fig. 1 showing one of the plows lowered; Fig. 3 is a detail horizontal section showing a top plan view of one of the plow beams 35 and its operating link; Fig. 4 is substantially a side view of the parts seen in Fig. 3; Fig. 5 is a disassembled perspective view of the elements shown in Figs. 3 and 4.

In the accompanying drawings, a main 40 frame 1 is shown which includes a pair of longitudinal side bars 2 connected at intervals by transverse bars 3 and supporting a platform 4 upon their rear ends, the front ends 5 of said bars 2 being spaced below a rectangular frame 6 which is secured to said bars by upright side brackets 7 and by a front bracket 8. (See more particularly Fig. 1.)

Non-rotatably held by the frame 6, is a 50 bearing ring 9 beneath which a fifth wheel 10 is mounted to rotate, said wheel carrying bearings 11 in which the short axle 12 of a steering wheel 13 is mounted, and having gear teeth 14 on its under side, said teeth 55 meshing with a gear wheel 15 which is keyed rigidly upon the forward end of a steering

rod 16 the latter extending rearwardly to a point above the platform 4 and being revolvably mounted in a bracket 17 which rises from one of the cross bars 3. The bracket 17 is 60 provided with a lateral extension 18 to which a curved locking arm 19 is pivoted, said arm having a nose designed to engage a squared portion 20 of the rod 16 when it is desired to lock said rod against rotation. 65 A stop pin 21 is provided on the extension 18 for limiting the outward movement of the arm 19. As shown in the drawings, the rear end of the rod 16 is provided with a steering wheel 22 which is located in advance 70 of a seat 23 supported upon the platform.

Secured above certain of the transverse bars 3, is a plurality of longitudinal stringers 24 to the intermediate portions of which bearings 25 and 25' are secured, the bearings 75 25 revolvably supporting the opposite ends of a transverse crank shaft 26 having a comparatively long crank 27 while the bearings 25' revolvably support the opposite ends of a rear crank shaft 26' having comparatively 80 short crank arms 27'. Spaced forwardly from the crank shafts 26 and 26', is a transverse operating shaft 28 from which a plurality of operating arms or cranks 29 depend while a single upright arm 30 rises from 85 said shafts and is connected by a link 31 with a main operating lever 32 which is located adjacent the platform and provided with a pawl and rack mechanism 33 whereby it may be locked in adjusted position. 90

For the details now to be described see more particularly Figs. 3, 4 and 5. A plurality of plow beams 34 are provided beneath the frame, said beams having their rear ends curved downwardly and secured 95 to suitably constructed plows 35. It will be noted that the rear ends of the beams 34 are notched as seen at 36 to receive the rear cranks 27', said notches thereby constituting half bearings, the latter being completed by 100 the provision of hook shaped plates 38 whose bills embrace the cranks 27' and coact with the notches 36 for forming complete bearings, said plates being secured by bolts 39 or other fasteners to the beams 34. The 105 lower edges of the plow beams 34 are notched as seen at 40, near their front ends, said notches receiving the cranks 27 and constituting half bearings, the other halves of said bearings being formed by hook shaped 110 plates 41 whose bills embrace said cranks on opposite sides of the beams. By reference

more particularly to Fig. 5, it will be seen that the bills of the plates 41 face in opposite directions and that said bills are prevented from moving downwardly in respect 5 to the beams, by laterally projecting stops 42 formed on the front ends of the beams.

Secured between the free ends of the plates 41 and projecting forwardly therefrom, are operating links 43 whose forward 10 ends are preferably forked and pivoted at 44 to the depending cranks or arms 29. By this construction, it will be seen that rocking of said cranks 29 by the lever 32, will rock the cranks 27 and 27' in directions to 15 raise or lower the plow beams, as the case may be. It will likewise be seen that, on account of the fact that the front cranks 27 are of greater length than the rear cranks 27' the front ends of the plow beams will be 20 tilted downwardly as seen in Fig. 2, thereby directing the plow points downwardly to cause them to be effectively retained in the ground. This last described operation constitutes a marked improvement in devices of 25 this general character in which the plows are prone to ride upwardly,

By reference to Figs. 2 and 3, it will be seen that the rear end of the frame 1 carries depending bearings 53 in which the 30 outer ends of crank shafts 52 are revolvably mounted, said crank shafts having depending cranks upon which oblique marking and earth working disks 54 are revolvably mounted and having other cranks 55 to which the 35 rear ends of links 56 are connected by oppositely facing hooks 57 similar to those designated by the numeral 41, the front ends of said links being forked and pivoted to certain of the arms 29, whereby the disks 40 will be raised and lowered simultaneously with the raising and lowering of the plows.

Although any appropriate means could be employed for supporting and driving the frame 1, a transverse drive shaft 100 is preferably provided, said shaft being revolvably mounted in bearings which rise from the main frame and having drive wheels 101 on its outer ends, said wheels being provided with internal gear teeth 102 with which 45 pinions on a transverse driven shaft 104 mesh, said pinions being normally loose upon

the ends of said shaft but being capable of rotating therewith when clutches are thrown in by proper operation of levers 106.

From the foregoing description, taken in connection with the accompanying drawings, it will be seen that comparatively simple mechanism has been provided for carrying out the objects of the invention, yet that an efficient device has been provided which possesses a number of advantageous features.

I claim:

1. The combination with a wheel supported frame of a trio of longitudinally spaced transverse shafts thereon, a comparatively long crank depending from the central shaft, shorter cranks depending from the front and rear shafts, a plow beam pivotally connected to the central and rear cranks, a link pivotally connected to the central and front cranks, and means whereby the latter may be rocked.

2. The combination with a wheel supported frame, of a front and rear crank depending therefrom, a plow beam connected to the rear crank and having a notch in one edge of its front end, said notch receiving one side of the front crank, an operating link in advance of said front crank, a hook shaped plate carried by said link and embracing the other side of said front crank, a stop on the beam for preventing the plate from moving vertically in respect thereto, and means connecting the rear end of the beam to the rear crank.

3. The combination with a wheel supported frame, a shaft having a crank, and an implement to be raised and lowered by rotation of said shaft, of an operating link having one end located adjacent the crank on said shaft, and a pair of plates secured to said link and having oppositely facing hooks embracing the crank.

In testimony whereof I have hereunto set my hand in presence of two subscribing witnesses.

JOHN A. ERICKSON.

Witnesses:

JAMES RIGLEY,
ALLIE L. CARLSTON.
